[57] CLAIM

The ornamental design for a container for food products, as shown and described.

DESCRIPTION

FIG. 1 is a front perspective view showing my new design for a container for food products,

FIG. 2 is a plan view thereof, the bottom view being a mirror image thereof; and,

FIG. 3 is a right side view, with the opposite side being a mirror image thereof, except for the angled edge of the raised pouch area.

1 Claim, 2 Drawing Sheets

FIG. 1

FIG. 2

FIG. 3
